(57) **CLAIM**

The ornamental design for a condensate catch basin, as shown and described.

DESCRIPTION

FIG. 1 is a perspective view of a condensate catch basin in accordance with the present invention;
 FIG. 2 is a top perspective view thereof;
 FIG. 3 is a bottom perspective view thereof;
 FIG. 4 is a top plan view thereof;
 FIG. 5 is a bottom plan view thereof;
 FIG. 6 is a right side elevation view thereof;
 FIG. 7 is a left side elevation view thereof;
 FIG. 8 is a front elevation view thereof;
 FIG. 9 is a rear elevation view thereof; and,
 FIG. 10 is a perspective view of the condensate catch basin shown in use with a condensate pump.
 The broken lines in the drawings depict portions of the condensate catch basin that form no part of the claimed design.

1 Claim, 8 Drawing Sheets
